GENERATING SYSTEM

Theodore J. Wilson, Minneapolis, Minn., assignor
to Minneapolis-Honeywell Regulator Company,
Minneapolis, Minn., a corporation of Delaware

Application June 26, 1944, Serial No. 542,100

8 Claims. (Cl. 322—36)

1

This invention relates to electrical generating systems and particularly to generating systems wherein provision is made for supplying a closely regulated voltage. The invention is particularly adapted for supplying a unidirectional potential of constant value.

It is an object of my invention to provide an improved electrical generating system capable of supplying an output voltage of relatively constant value.

It is a further object of my invention to provide a voltage regulating system devoid of any mechanically moving parts other than those of the generator itself, and one wherein the output voltage of the generator is regulated to a relatively constant value.

It is a further object of my invention to provide a low cost voltage regulating system of the thermionic type adapted to be manufactured economically in quantity and capable of furnishing satisfactory service over long periods of time, even when used under adverse conditions of vibration, dust, dirt or high altitudes.

It is a particular object of my invention to provide a regulating system devoid of any contacting apparatus inasmuch as such apparatus is disposed to failure under extreme conditions of altitude, low pressure, etc.

Other and particular objects of my invention are those inherently accomplished by the apparatus herein illustrated, described and claimed.

The apparatus is illustrated in the single figure of the drawing which is a wiring diagram schematically showing the electrical relationship of the various elements comprised in one embodiment of my invention.

Referring to the drawing, at 10 there is illustrated a generator of the direct current type having an armature 10a and a field 10b, one terminal of the armature being connected to an output line 11 at junction 15 and the opposite terminal being connected at junction 13 to ground 14, through line 12. One terminal of the field 10b is connected to junction 15 on output line 11. The other terminal of the field is connected to one output terminal 17 of the armature 20a of an accessory direct current generator 20. The remaining terminal 17a of 20a is connected through line 21 to junction 13 and thence to ground 14. The field 20b of the accessory generator is connected through lines 22 and 23 to output terminals 24 and 25 of a regulatory apparatus generally indicated by numeral 9 and hereinafter more fully described.

In the practice of my invention the main gen-

erator 10 and the accessory generator 20 are mechanically driven by any source of mechanical power generally designated by numeral 30 which may be an internal combustion engine, a steam engine, an electric motor, or other suitable driver. The mechanical connection between driver 30 and generators 10 and 20 may be by a single shaft represented by the line 31 or it may be through any suitable mechanical connection such as a belt 10 drive, if desired.

In the present embodiment of my invention the output line 11 is utilized for supplying a regulated unidirectional potential to any apparatus requiring a relatively constant voltage, for example, the battery A which is to be charged by generator 10. The positive terminal of battery A is connected to junction 26, and its negative terminal is grounded as at 27.

From junction 26 a line 32 extends to one 20 terminal of resistor 34, the opposite terminal of which is connected at junction 35 to ground 36. Resistor 34 performs the function of a potential divider, and to that end is provided with an intermediate tap 38, which may be adjustable if desired, and to which is connected a line 39 which extends to the positive pole of a standard battery 40. The negative terminal of battery 40 is connected through line 41 to the grid 42 of a thermionic amplifier tube generally designated 45. 30 Tube 45 is provided, in addition to grid 42, with a plate 48 and a cathode 43 which is arranged to be heated by a filament heater 44. Cathode 43 is connected through line 46 to junction 35 and hence to ground 36. Plate 48 is connected through a potential divider 51 and a resistor 53 to ground at 54.

Plate potential for tube 45 is obtained from a power supply circuit generally indicated at 61 and comprising potential divider 51, a filter condenser 56, one secondary winding 70 of a transformer 112 described in more detail below, and a thermionic tube 62 which includes a plate 66, a grid 65, a cathode 63, and a heater filament 64. The grid 65 and cathode 63 of tube 62 are shown 45 electrically connected to permit the tube to operate as a half-wave rectifier. Potential divider 51 is connected to form the load resistor of this rectifier circuit, and filter condenser 56 is connected in parallel with the divider 51 by means 50 of junction 58, conductor 59, junction 52, junction 50, conductor 49 and junction 57.

Under constant operating conditions, a substantially uniform D. C. potential difference is maintained around the end terminals of divider 55 51: the ripple component of the rectified cur-

rent is largely removed by condenser 56 if the latter is of sufficiently large capacitance. To the I. R. drop through divider 51 due to the flow of current in the rectifier circuit is added the drop due to flow of plate current in tube 45, the former drop being constant and the latter varying with change in the potential between grid 42 and cathode 43.

Of the total voltage drop through divider 51, any desired portion may be taken off by adjustment of variable tap 55 for establishing the cathode potential above ground potential, of a pair of tubes 80 and 90 comprised in a generator field supply circuit, generally indicated at 86, which will be presently described. The control grid potential of these tubes is ground potential as will presently be set forth, and is therefore more negative than cathode potential, since it is obtained through resistor 53 from the negative terminal of divider 51.

In addition to the two tubes just referred to, generator field supply circuit 86 includes filter condenser 124, one secondary winding 129 of transformer 112, and a phase shifting network generally indicated at 100. Tubes 80 and 90 are shown to be of the gas filled type and to comprise respectively, heater filaments 81 and 91, cathodes 82 and 92, screen grids 83 and 93, control grids 84 and 94, and plates 85 and 95. A line 74 leads from tap 55 on divider 51 to the cathodes and screen grids of tubes 80 and 90, to establish the cathode potentials of tubes with respect to ground 54.

Transformer 112 has a primary winding 113 which is suitably energized from any convenient alternating current source, controlled by a switch 143. The core of the transformer is illustrated at 114 and is provided with a plurality of secondary windings, the function of winding 70 having been previously mentioned. Secondary winding 116 serves to energize the heaters 46 and 64 of tubes 45 and 62, respectively. Secondary winding 118 similarly energizes the heaters 81 and 91 of tubes 80 and 90, respectively. Secondary winding 120 is provided with a center tap 121 which is connected to junction 24, previously mentioned, and through filter condenser 124 to junction 25, the latter being connected, through line 126, to line 74 at junction 77. Winding 120 is provided with end terminals 127 and 128, terminal 127 being connected through line 129 to the plate 85 of tube 80 and terminal 128 being connected through line 130 to plate 95. Winding 101 is center tapped as at 97, and is provided with terminals 102 and 103 for energizing phase shifter 100 to provide adjustable A. C. bias potential for the control grids 84 and 94 of tubes 80 and 90.

Phase shifter 100 comprises a bridge circuit of which two adjacent arms are comprised by halves of secondary winder 101; the remaining arms of the bridge include a variable resistor 108 and an inductor 105. Inductor 105 and resistor 108 are connected together at one terminal 106 which is grounded as at 110 through a current limiting resistor 109. To terminals 102 and 103, respectively, of secondary winding 101 are connected the other ends of inductor 105 and resistor 108. Terminals 102 and 103 are therefore the input terminals of bridge 129 and center tap 97 and terminal 106 are the output terminals of the bridge. Center tap 97 of secondary winding 101 is connected with the grids 94 and 84 of tubes 90 and 80 by line 29. A resistor 87 is connected at junction 88 to conductor 89 and grounded con-

ductor 74 to act as input resistor for tubes 80 and 90.

The electrical characteristics of the inductor and resistor are so chosen according to principles well known to those skilled in the art that a signal potential appears between junction 106 and tap 97 that is of a predetermined phase with respect to that across secondary 101, and by varying the value of resistor 108 from zero to infinity the phase angle between these potentials may be varied between 90 degrees and zero degrees. It will be observed that the output of secondary winding 120 is oppositely impressed upon the plate of tubes 80 and 90, while the output of phase shifter 100 is simultaneously impressed on the grids of both tubes.

From this arrangement it follows that by adjusting resistor 108 the point in the cycle of plate potential at which tubes 80 and 90 discharge may be varied, the current flow through field winding 20b varying in the same manner. It will also be apparent that tubes 80 and 90 are arranged for full wave energization of the generator field 20b in response to the signal on the grid of tube 45, as modified by the effect of the A. C. bias provided by the phase shifter.

The operation of the apparatus heretofore described will now be set forth.

The system is started by closing switch 143. After the tubes warm up to a temperature at which emission can take place, power supply 61 operates to provide plate voltage for tube 45. The grid of tube 45 is at its most negative value, however, since there is no I. R. drop through divider 34 to buck the voltage of standard battery 40. A minimum plate current therefore flows through tube 45, resulting in a minimum I. R. drop through divider 51—that due to operation of the rectifier being constant. For a given setting of tap 55, therefore, a minimum D. C. grid bias is applied to grids 84 and 94, and if variable resistor 108 is in its position of minimum resistance, maximum plate current flows through alternate tubes of the generator field supply on alternate half cycles of the current supplied to transformer 112, and maximum energization of field 20b is accordingly achieved.

Generator 10 is self-excited, and its field circuit includes armature 20a of auxiliary generator 20. When the driver 30 is started the voltage output of generator 10 is determined by the speed of driver 30 and the current through field 10b, the latter being additionally dependent on the output of generator 20 which is arranged to increase the current through field 10b due to the operation of generator 10a. As operation of driver 30 continues, voltage builds up between junction 26 and ground, and a portion of this voltage acts in the grid circuit of tube 45 to buck standard battery 40, thus reducing the negative bias on the tube and permitting increased current to flow in the plate circuit through divider 51. Increased negative grid bias is therefore provided for generator field supply tubes 80 and 90, and the plate current of these tubes is accordingly reduced, reducing the energization of field 20b and therefore the energization of generator 10. Thus, the increase in output of the main generator is continually opposed by decrease in its field excitation, until a point is reached at which further increase in output voltage is accompanied by such a decrease in excitation current as to reduce the output of the generator to its former value. Under these conditions, the circuit is in equilibrium, and of course in practice such equi-

librium is very rapidly attained. The setting of tap 38 determined the output potential reached by the regulator system, by determining the magnitude of current flowing in field 20b to bring about this equilibrium for a given voltage of standard battery 40, and also makes it possible to compensate for changes in the voltage of the standard battery.

If the system is in equilibrium and the speed of the driver drops, the voltage output of generator 10 begins to decrease and the grid bias of tube 45 therefore begins to increase. The current in field 20b immediately increases as fully described previously, to build up the field in the main generator, so that the voltage returns to normal.

Similarly, if the voltage between junction 26 and ground increases, the grid bias in tube 45 decreases, the plate current in tube 45 increases increasing the bias on tubes 30 and 90, the plate current in the latter tubes falls off, energization of generator field 20 is reduced, and the output voltage is again returned to normal.

Tap 55 is effective to vary the amount of change in the grid bias on tubes 80 and 90 brought about by unit change in the voltage being regulated, and therefore acts as a sensitivity adjustment as opposed to the zero adjusting function performed by tap 38.

It will be realized that variations in the grid bias of tubes 80 and 90 affected by tap 55 also influence the point on the characteristic curve of these tubes at which they operate, since the plate voltage remains the same: this affects the efficiency of the regulator. In order to make it possible to vary the sensitivity of this device without at the same time varying its efficiency, phase shifter 100 is provided. By adjustment of resistor 108, the portion of each cycle of the supply current during which tubes 80 and 90 discharge is varied. Therefore, a change in the voltage output due to adjustment of tap 55 may be compensated for to any desired extent by adjustment of resistor 108.

The structure and advantages of my invention have been fully and clearly set forth in the foregoing description, taken with the accompanying drawings, and the novel features thereof are pointed out in the appended claims. The disclosure, however, is illustrative only and I may make changes in detail, especially in matters of shape, size, and arrangement of parts, within the principle of the invention, to the full extent indicated by the broad general meanings of the terms in which the appended claims are expressed.

I claim as my invention:

1. A constant voltage direct current generating system comprising, in combination: a main generator having a main generator field; an accessory generator having an accessory generator field, said accessory generator being connected to supply a separate excitation potential to said main generator field; motor means for mechanically operating said main and accessory generators; and a control device comprising transformer means having a primary winding and a plurality of secondary windings, means adapted to energize said transformer with alternating current, a thermionic amplifier having cathode, anode, and control electrodes, rectifier means energizing the anode circuit of said amplifier from one of said transformer secondaries, a source of comparative potential, means adjustably connecting the output of said main generator, in opposed relation to said source of comparative potential, in the grid

circuit of said thermionic amplifier, an electronic full wave grid controlled rectifier providing energization for said accessory generator field from said transformer, and adjustable means and responsive means including said thermionic amplifier controlling the operation of said grid controlled rectifier, said first named rectifier means including a resistor in said anode circuit.

2. A constant voltage direct current generating system comprising, in combination: a main generator having a main generator field; an accessory generator having an accessory generator field, said accessory generator being connected to supply a separate excitation potential to said main generator field; motor means for mechanically operating said main and accessory generators; and a control device comprising transformer means having a primary winding and a plurality of secondary windings, means adapted to energize said transformer with alternating current, a thermionic amplifier having cathode, anode, and control electrodes, rectifier means energizing the anode circuit of said amplifier from one of said transformer secondaries, a source of comparative potential, means adjustably connecting the output of said main generator, in opposed relation to said source of comparative potential, in the grid circuit of said thermionic amplifier, an electronic full wave grid controlled rectifier providing energization for said accessory generator field from said transformer, and adjustable means and responsive means including said thermionic amplifier controlling the operation of said full wave rectifier, said adjustable means including and second means energizing said full wave rectifier from said transformer, said second means including means introducing time lag into cyclically varying currents passing therethrough, said responsive means including said thermionic amplifier.

3. A constant voltage direct current generating system comprising, in combination: a main generator having a main generator field; an accessory generator having an accessory generator field, said accessory generator being connected to supply a separate excitation potential to said main generator field; motor means for mechanically operating said main and accessory generators; and a control device comprising transformer means having a primary winding and a plurality of secondary windings, means adapted to energize said transformer with alternating current, a thermionic amplifier, rectifier means energizing the plate circuit of said amplifier from one of said transformer secondaries, a resistor in said plate circuit, a source of comparative potential, means adjustably connecting the output of said main generator, in opposed relation to said source of comparative potential, in the grid circuit of said amplifier, an electronic full wave grid controlled rectifier providing energization for said accessory generator field from said transformer, and adjustable means controlling the operation of said full wave rectifier, said last mentioned means including first and second means energizing said full wave rectifier from said transformer, said first means including said amplifier and said rectifier means, and said second means introducing means including time lag into cyclically varying currents passing therethrough.

4. A constant voltage direct current generating system comprising, in combination: a main generator having a main generator field; an accessory generator having an accessory generator

field, said accessory generator being connected to supply a separate excitation potential to said main generator field; motor means for mechanically operating said main and accessory generators; and a control device comprising transformer means having a primary winding and a plurality of secondary windings, means adapted to energize said transformer with alternating current, a thermionic amplifier, rectifier means energizing the plate circuit of said amplifier from one of said transformer secondaries, a variably tapped resistor in said plate circuit, a source of comparative potential, means adjustably connecting the output of said main generator, in opposed relation to said source of comparative potential in the grid circuit of said first amplifier, an electronic full wave grid controlled rectifier providing energization for said accessory generator field from said transformer, and responsive means adjustably controlling the operation of said full wave rectifier, said last mentioned means including said first amplifier, said rectifier and said resistor, said adjustable control being accomplished by variation of position of the tap of said tapped resistor.

5. A dynamo-electric generator having an armature and field means, and a voltage regulator for controlling the energization of said field in accordance with the generated voltage; said regulator comprising, amplifier means, a source of comparative potential, a variable impedance connected to the output of said generator, means directly connecting said source of comparative potential between the input of said amplifier means and the variable portion of said variable impedance, a pair of gaseous discharge devices each including cathode, anode and control electrodes, normally energized transformer means, means connecting said transformer means with the cathodes and anodes of said devices to impress thereon alternating potentials in opposed phase relation, means connecting said devices with said field means to cause variations in the current through said field means, variable coupling means connecting the output of said amplifier to the cathode and control electrode of each of said devices, and a source of alternating voltage of adjustable phase connected with said variable coupling means to form a series circuit between the control electrode and cathode of each of said discharge devices whereby a variation of said variable coupling or said alternating voltage of adjustable phase will adjust the sensitivity of said voltage regulator and the variation of said variable impedance will adjust the generated voltage of said generator.

6. A direct current generator having an armature and field means, and a voltage regulator for controlling the energization of said field in accordance with the generated voltage; said regulator comprising, an amplifier, a variable impedance connected to the output of said generator to provide voltage adjustment therefor, a source of comparative potential connected between the input of said amplifier and the variable portion of said variable impedance, a pair of gaseous discharge tubes each having a cathode, a plate and a control electrode, normally energized transformer means, means connecting said trans-

former to said tubes in a manner to energize the plates of said tubes in opposed phase relationship, variable coupling means connected between said amplifier and the control electrode and cathode of each of said tubes, an adjustable alternating current phase shifting device, means connecting said device to said transformer for energization therefrom, means connecting said device to said variable coupling means to form a series connection between the cathode and control electrode of each of said tubes to provide a sensitivity adjustment for said regulator, and means connecting the field means of said generator with said tubes for variable energization in accordance with the discharge of said tubes.

7. A constant voltage direct current generating system comprising, in combination: a main generator having a main generator field; an accessory generator having an accessory generator field, said accessory generator being connected to supply a separate excitation to said main generator field; and a control device comprising normally energized transformer means, an amplifier having cathode, anode and control electrodes, a source of comparative potential, means adjustably connecting the output of said main generator in opposed relation to said source of comparative potential in the grid circuit of said amplifier, a full wave grid controlled rectifier connected to said transformer for providing energization for said accessory generator, adjustable means connecting said amplifier to said rectifier to cause variable energization thereof, and an adjustable phase shifting means connected in circuit with said last named adjustable means for controlling the sensitivity of said full wave rectifier.

8. In a device for regulating the field energization of a dynamo-electric generator in accordance with the relation between the generated voltage and a standard voltage, in combination: voltage comparison means for comparing the relation between the generated voltage and the standard voltage for controlling the flow of current through a first electron discharge device; a pair of phase sensitive electron discharge means continuously energized with alternating voltage for variably energizing the field; a source of alternating biasing voltage of manually adjusted phase independent of said voltage comparison means for making adjustment of the conductivity of said pair of discharge means; and means including said first discharge device for variably biasing said pair of discharge means in accordance with the voltage derived from said voltage comparison means.
